UNITED STATES PATENT OFFICE.

ANTON BULLING, OF MUNICH, GERMANY.

VAPORIZER.

SPECIFICATION forming part of Letters Patent No. 678,714, dated July 16, 1901.

Application filed January 19, 1901. Serial No. 43,863. (No model.)

To all whom it may concern:

Be it known that I, ANTON BULLING, a citizen of Germany, residing at Munich, Germany, have invented certain new and useful 5 Improvements in Vaporizers; and I do hereby declare the following to be a full, clear, and exact description of the invention, such as will enable others skilled in the art to which it appertains to make and use the same.

10 This invention relates to an apparatus for vaporizing medicated liquids for inhaling-rooms and which may also be employed for regulating the temperature and for replenishing the air.

15 In the accompanying drawings, Figure 1 is a vertical section, partly in élévation, of my improved vaporizer. Fig. 2 is a horizontal section on line 2 2, Fig. 1; Fig. 3, a detail sectional elevation of the nozzle *b*; Fig. 4, a plan 20 thereof; and Fig. 5 is a vertical section, partly in elevation, of a modification of the vaporizer.

25 The vaporizer is designed to operate by means of compressed air in such a manner that a minute spraying of medicated liquids is obtained and that the other above-enumerated objects sought to be accomplished are properly effected.

30 The letter *a* represents a vessel adapted to receive the liquid to be sprayed and containing centrally a spraying-nozzle *b* and a number of blast-pipes *c g*, arranged at different elevations concentrically to nozzle *b*.

35 The spraying device consists of a stand-pipe *d*, which is connected by tube *e* with a tank or receptacle containing compressed air. The upper end of stand-pipe *d* enters the centrally-perforated hollow disk-shaped rose or nozzle *b*, the interior of which communicates 40 with a number of suction-pipes *f*, that enter the fluid in vessel *a*. Upon admitting the compressed air into tube *e* it will upon escaping through pipe *d* suck the liquid through pipes *f* and convert the same into a fine spray, 45 escaping through nozzle *b*. Owing to the peculiar construction and arrangement of this nozzle such a very fine spraying effect is obtained that with but one atmospheric pressure liquid drops cannot be found by a microscope 50 even in the center of the jet. The vertically-arranged blast-pipes are operated simultaneously with the atomizing-nozzle and are sup-

plied with compressed air by a second feed-pipe *h*. The jets of compressed air emitted by the pipes *c g* effect a further subdivision of the inhaling-liquid already sprayed by the nozzle *b*. Thus as such liquid enters the inhaling-chamber it will be in the form of the finest atoms, which possesses the further advantage that the occupants of such chamber 55 will not become wet. The blast-pipes *c g* may also be utilized for supplying the chamber in abundance with fresh bodies of pure air rich in oxygen. This prevents an accumulation of carbonic-acid gas, which is naturally formed 60 by the presence of a number of patients and which is very unpleasant and injurious.

Should a complete change of air be desired in the inhaling-chamber, this can be readily effected. It is only necessary to close the 65 feed-pipe *e* of nozzle *b*, to open the feed-pipe *h* of blast-pipes *c g*, and to open a window in the chamber, when a complete renovation of air will take place in a very short time. In an 70 equally simple manner the apparatus enables the temperature of the inhaling-chamber to be regulated. The air is naturally heated by being compressed within the compressed-air tank. If a cooling-worm is placed around the latter, through which cold water 75 is made to flow, the compressed air will be cooled and will enter the inhaling-room in a cooled state. If a cooling of the air is no longer desired, the flow of cold water through the worm surrounding the compressed-air tank 80 is stopped.

For sanitary reasons the air supplied to the apparatus should pass through a filter of wadding on its way to the tank.

The apparatus is provided with an open 85 frame *i*, projecting above the vessel *a* and supporting a removable lid *i*.

The air-blasts emitted from the pipes *c g* are blown into the spray in the same general direction as the flow of the spray. In this 90 way the spray is vaporized or diffused over a greater area and its impetus is greatly increased. It is obvious that the concentric arrangement of the blast-pipes is not a necessary condition for attaining this purpose. 95 It would be sufficient to let the dry air escape into the inhalation-room in a manner suitable for atomizing the spray. A simplified form of the invention embodying this 100

modification is illustrated in Fig. 5. Here the vessel *a*, containing the liquid and inclosing the nozzle *b*, is placed at any convenient place in the room. The compressed air is brought 5 in through the blast-pipe *g'* or through several blast-pipes *g' c'*, disposed at a suitable height above the atomizer. When the latter is started and dry air escapes through the pipes *g' c'*, the atomizing effect will be similar as with the concentric arrangement of the blast-pipes illustrated in Fig. 1.

I claim—

The herein-described vaporizer for rooms,

consisting of a chamber provided with a nozzle, means for feeding a liquid and compressed air to said nozzle to form a spray, and independent blast-pipes within the chamber adapted to subject the spray to the action of fresh bodies of expanding compressed air, as set forth and described.

In testimony whereof I affix my signature in presence of two witnesses.

ANTON BULLING.
